Richard Allison drdg. Bristol, Connecticut.

LETTER'S PATENT.

The schedule referred to in these Letters-Patent, and making part of the same containing a description in the words of the said Richard Allison of his invention in the mode of manufacturing metallic combs.

To all to whom these presents shall come: Be it known that I, Richard Allison drdg. of Bristol in the County of Hartford and State of Connecticut have invented a new and useful improvement in the mode of making and manufacturing Metallic Combs, that is in the manner of placing and confining the teeth to the plate, top or back of the comb, and that the following is an exact description thereof. Take a thin metallic plate suitable for the top or back of the comb, so that part of the plate in which the teeth are to be placed and confined, and which is to be the lower side of the back when finished, with a suitable wedge.

I make impressions for the teeth to be placed in lengthwise, These impressions or places for the teeth must be of a proper size according to the bigness of the teeth so that the teeth will exactly fit in and fill the places so as made up by that part of the plate to be turned up and placed upon the teeth, with similar impressions as hereafter described. At suitable distances from each other and at a proper distance from the lower edge of the plate, make a line of holes through the plate, the whole length of it, of the bigness of the teeth for them to be passed through.

The teeth are made of some metallic wire of a size required according to the bigness of the comb, & pierce

of wire long enough for two teeth, is bent at the middle and doubled, so as to bring the two parts parallel from where bent to the end of the teeth, and at a proper distance from each other that for the teeth without the comb is sufficient. This piece of wire forms two teeth and a suitable number of spaces double teeth, which pass through the holes made for them through the plate as before described. The lower part of the plate is then bent at the holes thro' which the teeth pass, and turned up so the teeth do not come back past the front part of the teeth, first about the edge of that part of the plate so turned up. This part of the plate so turned up is wedged down onto and between the teeth and the nail is driven into the impression made for the front of the teeth, so that part of the plate before it was bent and turned up. The teeth are then confined in the plate or back of the comb, by the two parts of the plate bent and turned and wedged together, and closing upon the teeth placed in the impression made for them as before stated. And they are confined and prevented from moving down by the lower part of the teeth, being passed above and acting on the edges of the plate turned up upon them, and from moving up by a notch or wedge made in the back to project up and fasten the front part of the teeth.

Or instead of making holes through the plate for the teeth to be passed through and turning up the lower part of the plate onto the teeth as before described, the object might be effected by putting a separate piece of plate of suitable length and width and placing it over the teeth, so as to extend on the plate or back of the comb and fastening and confining the two plates together with the teeth between them, with nuts or in some other way, thereby confining the teeth between the two plates so fastened

fastened together which plates form the top back of the comb.

What I claim as my invention and as previously known is not the comb or any particular shape, ridge or form of the comb but the manner of fastening and confining the teeth inward to the back or top of the comb by placing them inward between the two parts of a double plate fitted & prepared for those, and the two parts of the double plate connected together and made to set close upon the teeth, and made to confine the teeth from moving upward above by the edge of one part of the double plate being fast below the base or back of the teeth and by a ridge or neck in the plate just above the base or back of the teeth as before described.

The benefit and advantage of this invention and improvement is in saving of labour and expense in making metatic combs.

Dated at Plymouth the 1st day of June 1836,
Witness,

John Britton
George D. Gordon

Richard Allison Sues
